UNITED STATES PATENT OFFICE

154,916

DESIGN FOR AN ELECTRIC TOASTER

Montgomery Ferar, Detroit, Mich., assignor to
Noblitt-Sparks Industries, Inc., Columbus, Ind.,
a corporation of Indiana

Application July 9, 1948, Serial No. 147,472

Term of patent 7 years

(Cl. D81—10)

To all whom it may concern:

Be it known that I, Montgomery Ferar, a citizen of the United States, residing at Detroit, Wayne County, Michigan, have invented a new, original, and ornamental Design for an Electric Toaster, of which the following is a specification, reference being had to the accompanying drawing, forming a part thereof, in which Fig. 1 is a side elevation of an electric toaster embodying my new design; Fig. 2 is a top plan view of the toaster; and Figs. 3 and 4 are end elevations showing opposite ends of the toaster.

Both sides of the toaster are the same in appearance.

I claim:

The ornamental design for an electric toaster, as shown and described.

MONTGOMERY FERAR.
